UNITED STATES PATENT OFFICE

91,817

DESIGN FOR A CLOCK CASE OR SIMILAR ARTICLE

Joseph Gottlieb, Jersey City, N. J.

Application January 17, 1934, Serial No. 50,432

Term of patent 3½ years

all whom it may concern:

Be it known that I, JOSEPH GOTTLIEB, a citizen of the United States, and a resident of Jersey City, in the county of Hudson and State of New Jersey, have invented a new, original and ornamental Design for a Clock Case or Similar Article, which the following is a specification, referring being had to the accompanying drawing showing a part thereof.

Fig. 1 is a front elevation of a clock case showing my new design; and

Fig. 2 is a diagrammatic side view thereof.

I claim:

The ornamental design for a clock case or similar article, as shown.

JOSEPH GOTTLIEB.
